(57) **CLAIM**

The ornamental design for an ink cartridge, as shown and described.

DESCRIPTION

FIG. 1 is a reduced perspective view of an ink cartridge;

FIG. 2 is a partial perspective view thereof;

FIG. 3 is a front view thereof;

FIG. 4 is a top view thereof;

FIG. 5 is a right-side view thereof; and,

FIG. 6 is a rear view thereof.

The broken lines are for illustrative purposes only and do not form part of the claimed design.
